UNITED STATES PATENT OFFICE.

CHARLES L. PLUNKETT, OF MONTE VISTA, COLORADO.

CHICKEN COOP.

Application filed March 17, 1925. Serial No. 16,163.

To all whom it may concern:

Be it known that I, CHARLES L. PLUNKETT, a citizen of the United States, residing at Monte Vista, in the county of Rio Grande and State of Colorado, have invented certain new and useful Improvements in a Chicken Coop, of which the following is a specification.

This invention relates to an improved coop which has been especially, but not necessarily, designed for housing small chicks.

What I aim to do is to provide a suitably constructed housing provided with a depressible floor held normally in a predetermined position by a weight, the action of which is overcome when a certain number of chicks congregate upon the floor, there being a sliding door which is moved to a closed position under the action of the downwardly movable floor whereby to automatically govern the number of chicks permitted to enter the coop.

More specifically, I propose to provide a depressible floor, suspension means therefor, and a rockably mounted frame connected with the suspension means, the same being maintained in a predetermined position under the action of an adjustable weight, and there being a flexible connection between the rockable frame and a sliding door which is automatically closed when the frame is rocked in a predetermined direction under the action of the floor.

Other structural features and advantages may be derived from the use of the improved structure and same will become apparent from the following description and drawing.

In the accompanying drawings forming a part of this application and in which like numerals are employed to designate like parts throughout the same:

Figure 1 is a front elevation of a coop constructed in accordance with the present invention.

Fig. 2 is a horizontal section taken approximately on the plane of the line 2—2, Fig. 1, looking in the direction of the arrows.

Fig. 3 is a central vertical longitudinal section through the improved coop.

Fig. 4 is a transverse section.

Referring to the drawings in detail, it

will be seen that the reference character 1 designates generally a housing or coop of any suitable configuration and construction. The same may be of the construction shown, or of any appropriate construction and shape according to the circumstances confronted. As stated, the coop is especially designed to serve as a housing for small chicks.

In this connection I would recall that it is customary for groups of chicks to huddle together when roosting at night. Under such conditions they crowd each other to an extent to hinder their growth and well-being. In view of such circumstances, it becomes necessary to separate certain numbers of chickens to prevent overcrowding in the various small coops provided for their care.

In order to consume the least labor possible in overcoming this objection, I provide the housing shown with a depressible floor 2, the upward movement of which is limited by blocks 3 constituting stops. Connected to opposed longitudinal sides of the floor and extending vertically therefrom are substantially V-shaped suspension wires 4. Disposed over the apices of these wire members is a transversely arranged arch 5, the depending arms of which are provided with hooks 6 to engage with the apices of the suspension members.

Extending crosswise of the housing slightly in front of and at a plane below the bight portion of the arch is a stationary shaft 7. Rockably mounted upon this shaft is a substantially V-shaped weight carrying frame 8. In the present instance the frame has its arms provided with pivot eyes connected to the shaft. It will also be observed that the ends of the arms extending beyond the shaft are connected with the arch 5. If desired, appropriate braces 9 may be connected with the arch and frame and extended across the shaft 7. It will be noted that a rod 10 is connected to the apex of the frame 8, pivotally connected between its ends to shaft 7 and connected at its opposite end to the intermediate portion of the bight of the arch 5.

This rod is provided with a corrugated portion 11 forming a series of seats for reception of a counterbalancing weight 12. Under normal conditions the frame 8 is held, by the weight 12, in the downwardly in-

clined position shown in Fig. 3. Also shown here is a flexible cord or the like 13 which is connected to the apex of the frame, extended upwardly over a pulley 14 on the front wall of the housing and connected at its opposite end to a vertically sliding screen door 15. This door is adapted to close the entrance opening 16 in the front end of the coop.

This screen door may be set to automatically be counterbalanced and moved to open position under the influence of the weight. However under certain conditions to appear, it is gravity lowered to close the opening 16. Although it is not essential, I propose to provide a hand closed sliding door 17 to cover the opening 16 at night.

The operation is as follows: When a certain number of chickens enter the housing through the opening 16 and stand upon the 25 depressible floor 2, it will be seen that the same will move downwardly and through the medium of the suspension members 4 and arch 5 will serve to rock the weighted frame 8 upon its fulcrum, thus permitting the frame to take the dotted line position indicated in Fig. 3. In so doing, the screen door 15 lowers under the action of gravity to automatically close the opening and to trap the chicks in the housing. In this way 30 only a certain number of chickens are permitted to enter and this action can be controlled by adjusting the weight 12.

At night time, the door 17 can be closed by the care taker. The foregoing description taken in connection with the drawings, 35 will enable persons skilled in the art to which the invention relates to obtain a clear understanding of the same. Therefore, a more lengthy description is thought unnecessary.

Although I have shown and described the preferred embodiment of the invention, it is to be understood that minor changes coming within the field of invention claimed 40 may be resorted to if desired.

Having thus described my invention, what I claim as new is:—

1. In a chicken coop, a housing provided with an entrance opening, a sliding gravity lowered door for said opening, a depressible floor, side suspension members connected with said floor, an arch pivotally connected with said suspension members, a shaft supported in said housing, a frame pivotally mounted upon said shaft and connected with 50 said arch, means for adjustably mounting a weight upon said frame, a counterbalanced weight connected with said means, a flexible connection between said frame and door, and a pulley over which said means is passed. 60

2. In a chicken coop, a depressible floor, a pair of substantially V-shaped suspension members connected to the opposite sides of said floor, a relatively stationary horizontal supporting shaft, above said members, a 65 counter-balanced frame, pivotally mounted upon said shaft, and a connecting arch, the depending arms of which are provided with hooks, connected with the apices of said members, said frame being connected with the bight portion of said arch. 70

3. In a chicken coop, a housing provided with an entrance opening, a sliding gravity lowered door for said opening, a depressible floor, a pair of spaced parallel side suspension members connected in said floor, a relatively stationary shaft supported in said housing above said members, a frame pivotally mounted upon said shaft, a corrugated member carried by said frame, a weight including means for adjustably supporting it upon the corrugated member, an arched connector, the arms of which are connected to the aforesaid side suspension members, said frame being connected to the central portion 80 of said arch, and a flexible operating connection between said frame and door. 85

In testimony whereof I affix my signature.

CHARLES L. PLUNKETT.
